(57) **CLAIM**

The ornamental design for a water gun, as shown and described.

DESCRIPTION

FIG. 1 is a front, left, and top perspective view of a water gun, showing my design.

FIG. 2 is a rear, right, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a partial enlarged view of an area taken from the left side of FIG. 1 showing the honeycomb detail.

FIG. 10 is a partial enlarged view of an area in taken from the right side of FIG. 1 comprising a grip handle; and,

FIG. 11 is a partial enlarged view of an area taken from the right side of FIG. 2 showing the honeycomb detail.

The broken lines shown in the drawings are included for the purpose of illustrating portions of the water gun that form no part of the claimed design. The dash-dot broken lines represent the boundaries of the enlarged partial views of FIGS. 9-11 and form no part of the claimed design.
